UNITED STATES PATENT OFFICE.

CARL E. EKLIND, OF BERWYN, ILLINOIS, ASSIGNOR TO CAMEL COMPANY, OF CHICAGO, ILLINOIS, A CORPORATION OF ILLINOIS.

DOUBLE-ROLLER DOOR MOUNTING.

Application filed September 13, 1924. Serial No. 737,521.

To all whom it may concern:

Be it known that I, CARL E. EKLIND, a citizen of the United States, residing at Berwyn, in the county of Cook and State 5 of Illinois, have invented certain new and useful Improvements in Double-Roller Door Mountings, of which the following is a specification.

This invention relates to hangers or 10 mountings for doors of the type which open and close a doorway by movements in the plane of the door, and particularly to that type of door mountings in which a hanger or other form of bracket secured to the door, 15 is supported on a pair of rollers through the medium of a carriage pivoted to the bracket at an intermediate point in order to permit both rollers to maintain their bearing upon the track on which they travel.

20 The object of the present invention is to provide a construction of double roller door mounting of simple, cheap, durable and conveniently assembled construction, and especially adapted for use on freight cars or 25 in other situations where rough usage is encountered. Accordingly, the invention consists in providing a pair of rollers, bearing pins therefor, with or without interposed anti-friction elements, a carriage for the 30 rollers, a pivotal bearing for the carriage, and a hanger or bracket for attachment to the door, all brought together in their operative relations by what I shall herein term "progressive assembly". That is to say, the 35 rollers are confined against lateral displacement by introducing them into frame-like pockets formed in the carriage; the carriage is supported on the rollers by bearing pins passing transversely through the frames and 40 rollers; the bearing pins are secured in the frames, in at least one direction, by the assembly of the carriage with the hanger, one cheek of which overlaps the ends of the pins, confinement of said bearing pins in the other 45 direction being accomplished either by a shoulder on each pin abutting against the wall of the carriage frame, or by having a second cheek upon the hanger which overlaps the end of the pin; the carriage being 50 confined laterally with relation to the hanger preferably by introducing it between two cheeks with which the hanger is designed, and which are spaced apart by an offsetting web either above or below the 55 hanger, and pivotally confined against ver-

tical displacement in the space thus provided for it by means of a load-bearing pivot pin passing transversely through the cheeks and through the carriage; and the pivot pin being secured against displacement in one 60 direction by a shouldered abutment of the pin against one of the cheeks and in the other direction by fixing a key, in the form of a pin plate or the like, across the section of the pivot pin, and entering a hole in the pivot pin, when the key is at the shouldered end of the pivot pin or merely overlying the end of the pivot pin when located at the end from which the pivot pin is introduced. Inasmuch as the several features of the invention are applicable alike to top door 65 hangers and to bottom supports for doors, the term "bracket" as herein employed is to be taken as indicating either of said forms of mounting, and where the expression "hanger" is used, it is to be regarded as the equivalent of either of said forms.

In order that the invention may be fully understood, several embodiments thereof are illustrated in the accompanying drawings, in which

Figures 1 to 4 illustrate one embodiment of the present invention, Figure 1 being a front elevation of portions of a freight car body and its door, together with the door mounting; Figure 2 being a vertical section on the line 2^x-2^x of Figure 1; Figure 3, a vertical section on the line 3^x-3^x of Figure 1; and Figure 4 being a horizontal section on the line 4^x-4^x of Figure 1.

Figures 5 to 9 illustrate an embodiment of the present invention, designed particularly as a bottom support mounting for doors, Figure 5 being a front elevation of portions of a freight car body and its door, with the mounting applied thereto; Figure 6, a vertical section on the line 6^x-6^x of Figure 5; Figure 7, a vertical section on the line 7^x-7^x of Figure 5; Figure 8, a horizontal section on the line 8^x-8^x of Figure 5; and Figure 9, a view similar to Figure 7 but with slightly modified construction, illustrating the use of a bushing between the roller and its journal pin, instead of anti-friction rollers.

Figures 10 to 12 illustrate an embodiment of the invention as applied in a situation similar to that illustrated in Figures 1 to 4, but showing a different construction of bracket or hanger and a different method of

securing the pivot pin, Figure 10 being a front elevation of a freight car body and its door with the mounting applied thereto; Figure 11, a vertical section on the line 5 11^x—11^x of Figure 10; and Figure 12, a top plan view with the car body in section on the line 12^x—12^x of Figure 11.

Figures 13 and 14 are, respectively, a front elevation and top plan view of the 10 hanger substantially as employed in Figures 10 to 12, but having modified construction 15 of confining key for the pivot pin.

Figure 15 is a view corresponding generally to Figures 2 and 11, but showing a modified construction of pivotal support of the 20 bracket or hanger upon the carriage, and means for securing the carriage thereon.

Referring to Figures 1 to 4, A represents a portion of a freight car body equipped 25 with a known construction of channel-iron track B for a door mounting, and C represents a portion of a door associated therewith through the medium of a bracket 1 and a pair of rollers 2 on which said bracket is 30 supported through the medium of a carriage 3 pivotally connected with the bracket through the medium of a load-sustaining pivot pin 4. These elements have heretofore been employed in the same general 35 relationship as herein illustrated; but the present invention involves novel and advantageous features in the construction of several of these elements and in the method of their assembly, which will not be described.

As shown more clearly in Figure 4, carriage 3 is constructed on either side of its hub 5, with a frame 6, providing a bracket 7 into which the roller 2 is introduced vertically and by which the roller is confined 40 laterally, and a journal pin 8 by means of which the roller is confined within its pocket, imparts its load, and is passed through the side walls 9, 10, of the frame-like end of the carriage.

The carriage 3 is assembled with the bracket 1 by introducing it vertically into the pocket 18 defined by the front cheek 11 and rear cheek 12, and offsetting web 19 of the bracket, and securing it there, with freedom of pivotal action, through means of the pivot pin 4 which passes transversely through both cheeks and the intervening carriage hub 5; and in order that this assembly of the carriage with the bracket may 50 serve to hold the journal pins 8 in place and render unnecessary other means for securing the pins in the walls of the carriage, bracket 1 is constructed, preferably at the front, with laterally extending ears 13 that 55 overlie the ends of pins 8; the opposite ends of said pins being confined against movement in the direction away from the confining ears 13, according to the present embodiment, by seating said pins in the rear 60 walls 10 of the pockets, through the me-

dium of squared and shouldered ends 14. The journal pins may, however, as herein-after described with reference to Figures 5 to 9, inclusive, be confined at both ends by overlapping cheek extensions. Pivot pin 4 70 is confined against axial displacement with front and rear cheeks 11, 12, according to the present embodiment, by means of a cotter or other pin 15 passed diametrically through the pivot pin beyond one of the 75 cheeks, for instance the front cheek 11, thereby securing the pin against movement in one direction; movement of the pin in the opposite direction being resisted by providing the end of the pin with a squared 80 and shouldered construction as shown at 16, and which enters the correspondingly formed seat in the bracket cheek.

From the foregoing it will be seen that the several elements of the door mounting 85 are so constructed that they can be progressively assembled in the sense that each member is secured in place by the introduction of the member that follows it, only the last member, namely the pivot pin, requiring the 90 use of special securing means. It will also be seen that by utilizing the squared and shouldered ends 14 on the journal pins 8 and the similarly constructed end 16 on the pivot pin 4, as the means for seating said 95 pins against axial movement in one direction, said pins are prevented from rotating in the parts in which they are mounted, and thus wear is restricted to the surface of the pin and prevented from taking place in the 100 mountings.

It will further be seen that the method of assembly of the rollers with the carriage admits of the use of antifriction elements 17 between the rollers and their journal pins, 105 which elements, like the rollers 6, are confined by the mere introduction of the parts in position.

According to Figures 5 to 9, inclusive, which show the invention as applied to a 110 bottom support for doors, the bracket 1^a has its front cheek 11^a developed laterally into a form which adapts it to serve as the means of attachment to the door C', and the rear cheek 12^a, offset therefrom by the web 115 19, is likewise developed laterally until it forms the rear wall of the pocket 18^a in which the carriage 3^a is confined. Thus, as shown more clearly in Figures 7 to 9, cheeks 11^a, 12^a, constitute the means of confining journal pins 8^a in both axial directions, in their bearings in front and rear pocket walls 9^a, 10^a, while leaving the latter to confine the rollers 2^a as well as their anti-friction 120 elements which may be in the form of an annular series of rollers 17^a as shown in Figure 7, or a mere bushing 17^{ax}, as shown in Figure 9. As shown in Figures 5, 6, 7 and 9, pivot pin 4^a, instead of being seated through squared and shouldered end as 125 130

in Figure 1 to Figure 4, may be held in both directions by the key pin 15^a which passes through not only the pivot pin but through the hub-like cheek extension 11^{ax}.

- 6 According to Figures 10, 11, and 12, bracket 1^b functioning in all respects similarly to the bracket 1 disclosed in Figures 1 to 4, has its front cheek 11^b and rear cheek 12^b spaced apart by the web 19^b located beneath the carriage 3^b instead of above it, as in previously described forms; a key pin 15^b, mounted in ribs 20 upon the front cheek 11^b, merely lies across the front end face of the pivot pin 4^b, inasmuch as the squared and 15 shouldered end 16^b of the latter is seated in the rear cheek 12^b. In this form, the assembly of the rollers 2^b with the carriage 3^b, is in all respects substantially as described in connection with Figures 1 to 4.
- 20 According to Figures 13 and 14, key pin 15^c is in the form of a narrow strip or plate inserted in lugs 20^c so that it lies across the forward face of the pin 4^c, which latter is otherwise constructed and assembled as 25 shown in Figures 10 to 12. In Figures 10 to 14, the front cheek 11^c has lapping ears 13^c for confinement of the journal pins 8^c, just as described in connection with Figures 1 to 4.

- 30 As shown in Figure 15, the carriage 3^d with its rollers 2^d mounted therein, and which will be assumed to follow the teachings of Figures 1 to 4 and 10 to 12, may be mounted on the bracket 1^d without the 35 use of the rear cheek, namely by constructing the front cheek 11^d with an integral pivot journal 4^d to receive the hub 5^d of the carriage, and the latter may be confined upon said integral pivot journal by means of 40 a washer 21 or the like and rivet 22.

I claim:

1. In combination, a pair of rollers, journal pins in said rollers, a carriage in which said journal pins are mounted, a bracket, 45 and a pivot pin supporting said bracket upon said carriage, said bracket being constructed to confine the journal pins in said carriage.
2. The combination of a pair of rollers, pins upon which said rollers revolve, a carriage constructed with pockets receiving said

rollers and having side walls in which the ends of said journal pins are mounted, a bracket overlying the ends of said journal pins and confining them in the carriage, and 55 a pivot pin securing said bracket to said carriage.

3. In a door mounting, a pair of rollers, a carriage constructed with frame-like ends providing pockets receiving said rollers by 60 vertical assembly, and having side walls confining said rollers in the direction of their axes, journal pins passing through said side walls and intervening rollers, a bracket adapted to said carriage and having a cheek 65 which overlies the ends of the journal pins and confines them in said side walls, and means for securing the bracket to the carriage.

4. In a door mounting, a pair of rollers, a carriage, journal pins mounting said rollers in said carriage, and a pivot pin for mounting the bracket upon the carriage; said bracket having front and rear cheeks providing a pocket in which said carriage 70 is received, said pivot pin passing through said cheeks and the intervening carriage.

5. In a railway mounting for doors, a pair of rollers, a carriage having walls between which the rollers are confined, pins passing through the walls and supporting the rollers therein, a bracket pivotally mounted upon the carriage at a point intermediate of the rollers, and lateral extensions on the bracket, overlying the ends of the pins and confining 80 the pins in place in the carriage, while leaving the extensions free to partake of swinging movements of the bracket.

6. In a railway mounting for doors a pair of rollers, a carriage mounted on said rollers, a bracket, and means for connecting said bracket with said carriage comprising front and rear cheeks on the bracket, a pivot pin passing through one of said cheeks, then 85 through the intervening carriage, and having a shouldered end through which it is seated in the other cheek, and a key pin extending across a section of said pivot pin.

Signed at Chicago, Illinois, this 6th day of September, 1924.

CARL E. EKLIND.
